UNITED STATES PATENT OFFICE.

FRANK SIMEK, OF ASTORIA, NEW YORK, ASSIGNOR OF ONE-HALF TO REINHOLD A. SCHMIDT, OF BROOKLYN, NEW YORK.

HORSESHOE.

1,200,037.

Specification of Letters Patent.

Patented Oct. 3, 1916.

Application filed June 17, 1916. Serial No. 104,169.

To all whom it may concern:

Be it known that I, FRANK SIMEK, a subject of the Emperor of Austria, and a resident of Astoria, in the county of Queens and State of New York, have invented certain new and useful Improvements in Horseshoes, of which the following is a specification.

This invention relates to improvements in horseshoes and particularly of that type in which removable calks are used.

The principal object of the invention is to provide a shoe of the class described which may be permanently attached to the hoof of a horse, provisions being made whereby both the heel and toe calks are separable from the shoe body.

A second object is to provide means whereby the toe calk is supported in an adequate manner in all directions, the same being removable without the use of tools or appliances of any kind.

These and other objects are attained by the novel design and construction of shoe herein described and shown in the accompanying drawings, forming a material part of this specification, and in which:—

Figure 1 is a perspective view of a horse's hoof in the act of engaging with a roadway, illustrating the application of the invention. Fig. 2 is a perspective view of the shoe, looking from the lower side thereof. Fig. 3 is a sectional view taken on line 3—3 of Fig. 2. Fig. 4 is a similar view showing a modified form of toe calk. Fig. 5 is a like fractional view showing a calk-holding means. Fig. 6 is a perspective view of a preferred form of toe calk. Fig. 7 is a similar view of the calk shown in Fig. 4, and Fig. 8 is a fractional plan view of the shoe toe.

The construction indicates the use of a shoe 10 substantially of the ordinary pattern having depressed recesses 11 in its outer lateral edges through which are perforations to receive the nails for securing the shoe in position on the hoof.

The heel calks 15 are attached by means

of screw-threaded shanks 16 suited to engage in openings near the heel extremities of the shoe, and may be made of rectangular shape to which a wrench can be applied, the calks terminating in pyramidal points 17, or flat if preferred as shown at 18.

The upper front part of the shoe 10 is provided with an integral clip 20 suited to contact with the point of the hoof in a customary manner, while on the opposite, lower side is formed a solid abutment 21 containing an opening 22 of rectangular cross section having obliquely disposed lateral walls 60 forming in effect a tapered recess adapted to contain the truncated flattened pyramid 23 of the toe calk 24 which is preferably made with one beveled side, the opposite outer side being straight.

If desired, the toe calk may have a flattened outer surface 25 as shown in Fig. 7. These calks are adapted to be inserted merely by pressure, as the weight of the animal on the pavement in itself tends to force 70 the calk shank firmly into engagement with the opening, maintaining it rigidly in engagement. When, however, it becomes desirable to loosen the same it is accomplished very readily by striking on the ends, thereby loosening the calk so it will drop freely out. This arrangement allows for calks of different shapes to be inserted with the utmost readiness, thereby saving loss of time and expensive, frequent visits to a blacksmith or farrier, as will be readily understood.

In order to provide against the possible loosening of the calk it may have an indentation 26 formed in the inner side of the 85 shank 23, a spring detent 27 being secured in a recess 28 formed in the abutment 21 and provided with a hooked point 29 adapted to enter and engage in the indentation, a clip 30 being provided by means of which the 90 spring detent can be released from engagement with the calk, the construction being substantially as indicated in Figs. 5 and 6.

Having thus described my invention,

what I claim as new and desire to secure by Letters Patent, is:—

In a horseshoe, the combination with the body thereof, of an abutment extending along the toe below said body, a beveled walled recess formed through said abutment body, a spring detent secured in said recess, a toe calk, a shank formed with said calk,

said shank being suited to said recess, and means formed in said shank receptive of 10 said detent.

Signed at New York, in the county of New York, and State of New York, this 27 day of May, 1916.

FRANK SIMEK.
